UNITED STATES PATENT OFFICE

BEN A. BALL, OF PAWTUCKET, RHODE ISLAND, ASSIGNOR TO AMERICAN TEXTILE COMPANY, INC., OF PAWTUCKET, RHODE ISLAND, A CORPORATION OF RHODE ISLAND

DESIGN FOR LACE

Application filed July 24, 1930. Serial No. 36,453. Term of patent 7 years.

To all whom it may concern:

Be it known that I, BEN A. BALL, a citizen of the United States, and a resident of Pawtucket, in the county of Providence and State of Rhode Island, have invented the new, original and ornamental Design for Lace, of which the following is a specification.

Reference is had to the accompanying drawing, in which the figure is a plan view of a piece of lace showing my new design, the dot-and-dash line indicating one repeat.

I claim:

The ornamental design for lace, substantially as shown and described.

BEN A. BALL.
